DOWEL SUPPORT FOR CONCRETE PAVEMENT EXPANSION JOINTS

Filed Dec. 21, 1936

UNITED STATES PATENT OFFICE

2,133,553

DOWEL SUPPORT FOR CONCRETE PAVEMENT EXPANSION JOINTS

Chester A. Lord, Chicago, Ill., assignor to Universal Form Clamp Co., Chicago, Ill., a corporation of Illinois

Application December 21, 1936, Serial No. 116,898

6 Claims. (Cl. 94—8)

This invention relates to the art of concrete pavement expansion joints of the known type wherein the meeting ends of the pavement at the joint have embedded therein dowels extending across the joint and usually coated with grease on one side of the joint to permit relative slip as the concrete expands or contracts under temperature changes. In the use of such dowels it is essential to the proper functioning that they be located accurately parallel to the axis of the pavement.

It has been the practice heretofore to rest the end portions of the dowel bars on supports known as chairs, either directly, or on cross rods extending between and seated on the chairs of each row on each side of the joint. The chairs include a pointed leg or legs that are driven into the dirt bed or floor on which the concrete is spread, and if, as often happens, the chairs of a row are not set to the same depth or one or more of them accidentally gets depressed too far into the bed or floor, it throws the dowel bars out of parallelism. One object of this invention has been to provide an improved structure of chair that can be easily and cheaply bent to shape from a single length of heavy wire. Another object has been to provide an improved chair structure by which the leg or legs of the latter can penetrate the bed only to a predetermined distance. Another object has been to provide an improved structure of dowel bar support by which the several chairs of each row are tied to each other in fixed spaced relation and so that adjacent chairs in the same row cannot tilt toward or from each other. Still another object has been to provide an improved dowel bar support wherein the two rows of chairs are maintained parallel and at fixed distances from each other and from the pavement joint.

Other objects and advantages of the invention will be apparent to persons skilled in the art from the following detailed description, taken in connection with the accompanying drawing wherein I have illustrated preferred embodiments of the invention, and in which—

Fig. 1 is a perspective view of the preferred form of chair, with a dowel bar and its supporting cross bar fragmentarily indicated by dotted lines.

Fig. 2 is a fragmentary perspective view of the joint packing and reinforcing assembly, employing the form of chair shown in Fig. 1.

Fig. 3 is a top plan view, on a reduced scale, of the complete assembly, the concrete pavement being fragmentarily indicated by dotted lines.

Fig. 4 is a fragmentary section, crosswise of the

joint, showing the packing and reinforcing assembly embedded in the meeting ends of the concrete.

Fig. 5 is a perspective view, similar to Fig. 1, of a modified form of chair.

Referring to the drawing, and first describing the form of chair shown in Figs. 1 and 2, said chair is preferably a one-piece structure consisting of a single length of heavy wire bent to form a pair of downwardly divergent legs 10, a lateral support 11 for a dowel bar laid between the limbs thereof, said limbs being continuous with the upper ends of the legs 10, and a seat 12 formed by contiguous twin limbs for a cross bar extending between adjacent chairs of a single row and itself forming a direct support for the dowel bar. The lower ends of the legs 10 are, of course, designed to be impressed into the dirt bed on which the pavement is laid.

As shown in Fig. 2, round cross bars or rods 13 are laid in the seats 12 of the chairs of each row, and the dowel bars 14, which extend across the joint are directly supported adjacent to their ends on the cross bars 13 and extend through the lateral dowel bar supports 11. P and P' (Fig. 4) designate the end portions of the pavement sections on the two sides of the joint, and S designates the usual flat slab of asphalt or like material that is commonly inserted as a packing between the meeting ends of the concrete sections. This slab is formed with transverse holes 15 through which the dowel bars 14 extend.

In prior constructions with which I am acquainted, the chairs of each row, whatever their structure, have been independent units, entirely unconnected except for the cross bars 13 occupying the seats of the chairs. As hereinbefore stated, unless the chair seats of the two rows are kept at substantially the same level, obviously the dowel bars 14 will not be in perfect parallelism which is essential to a good expansion joint of this character. To obviate this fault, I provide in association with each row of chairs a rod 16 which extends lengthwise of the row and is secured, preferably by spot or tack welding to the legs of the chairs a slight distance above the lower ends of the legs. This rod 16 serves two useful functions. In the first place, it limits the depth of penetration of the chair legs into the pavement bed, so that all of the chairs will be impressed to the same extent into the bed, thus maintaining their seats 12 on a common level; and in the second place, it rigidly connects and spaces the several chairs of each row so that they cannot tilt toward or from each other.

The two dowel bar supporting structures are preferably located at equal or substantially equal distances from the joint and in parallelism with the joint and each other. To insure this accurate disposition of the two rows of supports, I employ means for rigidly connecting them across the joint. The means preferably used and herein illustrated consists of cross rods 17 extending across the joint and disposed at spaced intervals lengthwise of the two supporting structures, the ends of said rods 17 being secured as by spot or tack welding to the rods 16. Preferably, and as herein shown, each rod 17 is formed substantially midlength thereof, with a downward U-shaped offset 18, which seats and embraces the lower edge portion of the packing slab S.

In Fig. 5 I have illustrated a slightly modified form of the one-piece chair, wherein the seat 12' for the cross bar 13, instead of being formed as a continuation of the lateral dowel bar support 11, is formed as a lateral offset of one of the legs 10. While the form of chair illustrated in Figs. 1 and 2 is preferred, the form shown in Fig. 5 may be substituted therefor to practically the same effect if desired.

By virtue of the described construction, the dowel bars 14 can never get out of true parallelism either when erecting the chairs or when pouring the concrete; and by rigidly connecting the chairs of each row and also the pairs of rows, the entire joint reinforcing structure retains its form and correct position when and after the concrete is spread.

While I have illustrated and described a preferred embodiment of the invention, it is manifest that many of the structural details may be varied without departing from the operative principle of the invention, and hence I do not limit the latter to the specific form shown, but reserve all such variations, modifications and mechanical equivalents as fall within the spirit and purview of the claims.

I claim:

1. A two-legged dowel bar supporting chair for concrete pavement extension joints, consisting of a single length of wire bent to form a pair of legs consisting of end portions of the wire disposed in a common plane, a lateral support for a dowel bar located between and in the plane of said legs, and a cross bar seat laterally offset from the plane of said legs and lateral support.

2. A two-legged dowel bar supporting chair for concrete pavement expansion joints, consisting of a single length of wire bent to form a pair of legs consisting of end portions of the wire disposed in a common plane, a lateral support for a dowel bar located between and in the plane of said legs, and a cross bar seat

formed by contiguous twin U-shaped limbs, continuous with said lateral support and laterally offset from the plane of said legs and lateral support.

3. A two-legged dowel bar supporting chair for concrete pavement expansion joints, consisting of a single length of wire bent to form a pair of legs consisting of end portions of the wire, a lateral support for a dowel bar continuous with the upper ends of said legs and lying between and in the plane of the latter, and a cross bar seat formed by a laterally offset portion of one leg located between the upper and lower ends of the latter.

4. In a continuous spacer and support for dowel bar assemblies for concrete pavement expansion joints, the combination with parallel rows of chairs disposed respectively on opposite sides of the joint, each chair having a leg formed with a free lower end adapted to be driven into the dirt bed of the pavement and the legs of all the chairs in each row being located in a common plane transverse to the roadway, of rods extending across and secured to the lower portions of the legs of the chairs of the two rows respectively, and means connected to said rods extending across the joint and rigidly connecting and spacing said rows.

5. In a continuous spacer and support for dowel bar assemblies for concrete pavement expansion joints, the combination with parallel rows of chairs disposed respectively on opposite sides of the joint, each chair having a pair of legs formed with free lower ends adapted to be driven into the dirt bed of the pavement and the legs of all the chairs in each row being located in a common plane transverse to the roadway, of rods extending across and secured to the lower portions of the legs of the chairs of the two rows respectively, and rods connecting and spacing said first-named rods across the joint.

6. In a continuous spacer and support for dowel bar assemblies for concrete pavement expansion joints, the combination with parallel rows of chairs disposed respectively on opposite sides of the joint, each chair having a pair of legs formed with free lower ends adapted to be driven into the dirt bed of the pavement and the legs of all the chairs of each row being located in a common plane transverse to the roadway, of rods extending across and secured to the lower portions of the legs of the chairs of the two rows respectively, and rods connecting and spacing said first-named rods across the joint, said last named rods formed with downwardly offset portions adapted to seat and embrace the lower edge portion of a joint packing slab.

CHESTER A. LORD.
